TOY REVOLVER WITH LABYRINTH SEAL FOR EXPLOSIVE CAPS

Giampiero Ferri and Jori Marinai, both of
Via Stoppani 38, Florence, Italy
Filed July 6, 1964, Ser. No. 380,302
10 Claims. (Cl. 42—58)

This invention relates to toy guns, and particularly, but not exclusively, relates to toy pistols for housing explosive caps in the form of small cups with an explosive charge in the bottom.

It is an object of this invention to provide a toy gun having a rotatable cylinder supporting a member having a plurality of firing pins extending therefrom and which are adapted to receive explosive caps, the caps being detonated by a hammer, the cylinder together with the firing pins being movable to the side of the gun body so as to permit the exploded caps to be ejected from the pins.

It is a further object of this invention to prevent the flames produced as a result of one cap exploding causing caps on adjacent firing pins to be exploded.

In order that the invention can be fully understood, one constructional form thereof will now be described, by way of example, with reference to the accompanying drawings, in which:

FIG. 1 shows a longitudinal sectional view of a cylinder and ejector in a toy gun according to the invention;

FIG. 2 is a view of the cylinder and ejector similar to FIG. 1, but shows the ejector protruding to enable the caps to be ejected;

FIG. 3 shows an end view along the plane III—III of FIG. 2;

FIG. 4 shows an axial section of the cylinder alone;

FIG. 5 shows a cross-section along the plane V—V of FIG. 4;

FIG. 6 shows an axial section of the ejector alone; and

FIG. 7 shows a cross-section along the plane VII—VII of FIG. 6.

Referring now to the drawings, a bearing 1 is pivotally and slidably mounted at 1a in order to allow the cylinder 2 to be displaced sideways relatively to the body of the gun. The bearing is integral with a bored spindle or sleeve 1b, the cylinder 2 being rotatably mounted about this spindle. The cylinder 2 is substantially cylindrical and has a plurality of openings 3 bored through its periphery parallel to its axis. These housings terminate at the rear side, that is, on the side of the hammer, in a hollow 4. The cylinder 2 has, in addition, a central bore 5 which terminates in a narrow passage formed by a collar 5a (see in particular FIG. 4). A plurality of projections 6 extend radially inwardly from the periphery of the cylinder constituting a separating member between one opening 3 and the other. In addition, a bracket 7 protrudes outwardly into each opening 3. A plurality of teeth 8 are formed on the rear side of the cylinder in order centrally to locate this cylinder with respect to the hammer after its release.

Housed in the hollow 4, and slideable along the axis of the cylinder, is an ejector 9 which has a series of radially outwardly extending projections 10. Anvils 11 extend axially from the ends of these projections and each is adapted to receive a cup-shaped cap. The ejector has an annular groove 12 which encircles an axial tubular extension 13. The thickness of this extension is relatively small and its outer diameter is such as to allow its insertion within the collar 5a.

On its outer surface the ejector 9 has a plurality of teeth 14 for cooperating with a pawl such as shown for example in FIG. 4 of Brubaker Patent No. 2,088,891, for rotating the cylinder each time the hammer is operated,

2

the cylinder being drawn by the ejector 9 which engages with it. In this operation the projections 10 extend into the passages between the openings 3 and the central bore of the cylinder so that they are housed between the projections 6 and cooperate with them in such a way as to create a labyrinth seal, generally indicated by L in FIG. 3. These seals prevent flames, originated by the explosion of a cap under percussion from the hammer, spreading to the adjacent caps.

In correspondence with the projections 10 curved parts 10a are formed, these parts being shaped in such a way that when the ejector 9 is inserted in the hollow 4 the housing is completed around the anvil 11.

A hollow multi-stepped stem 16 is mounted within the spindle 1b to align with the cylinder in the firing position. This stem houses a shaft 17 which projects beyond the inner extremity of the stem to receive a tubular member 18 after the cylinder 2 and ejector 9 have been assembled. Once assembled, the ejector 9 is housed in the hollow 4, the tubular extension 13 embraces the inner extremity of the stem 16, and a boss on the member 18, supported on the shaft 17, is partially in engagement with the walls of a bore in the ejector 9. Before inserting the stem 16 and shaft 17, the cylinder 2 and ejector 9 are assembled, and the upstanding rim on the end of the tubular extension 13 is inwardly deformed so as to enable it to be pressed through the collar 5a, this collar then preventing the cylinder and ejector from coming apart.

In addition, the stem 16, together with the shaft 17, and the member 18 are only permitted to move by an extent determined by the boss on this spindle and the inner end of the stem 16. With this arrangement, when the ejector 9 is housed inside the hollow 4, the member 18 can either lie flush with the end of the ejector 9 or project from this end, as shown in FIG. 1, to locate the cylinder in position in the pistol. When the caps are to be extracted, the member 18 is caused to move fully inside the ejector 9 and the bearing 1, together with the cylinder, is rotated sideways about its pivot 1a. Subsequently, the stem 16 is pushed inwardly so as to move the member 18 into the position shown in FIGURE 2 whence the spent caps are ejected, this movement being limited by the rim on the extension 13 abutting the collar 5a.

The whole arrangement is thus constituted by two main parts, namely, the cylinder and the ejector. The flames exhaust readily through the openings 3 and do not tend to be exhausted towards the adjacent openings and the path followed by the flames inside the labyrinth L is such as to cause the flames to be extinguished before reaching the vicinity of the nearby caps.

The anvils 11 are sufficiently supported by the brackets 7 and by the rear end of the cylinder to ensure explosion of a cap on the appropriate anvil struck by the hammer and resist the shocks caused by the hammer. The various parts may be easily manufactured by means of die casting, the coupling between the parts being obtained by force fits.

We claim:

1. A toy gun comprising a body, a hammer pivotally mounted on the body, a cylindrical housing defining a plurality of apertures adjacent its periphery, housing-supporting means mounted on said body for supporting said housing for rotational movement, said means being selectively movable, together with said housing, between a first position in said gun body and a second position projecting from said gun body, a plurality of anvils coaxially mounted on said housing for supporting explosive caps, each said anvil being disposed within one of said apertures,

means mounted between said hammer and said anvils for successively aligning the anvils with said hammer in response to successive operations of the hammer,

means projecting inwardly of the outer wall of said housing between adjacent apertures, and means located inwardly of each of said apertures and partially encircling said anvils, said latter two means cooperating to substantially complete a housing around each anvil and to form a labyrinth seal whereby adjacent caps are shielded from an exploding cap.

2. A toy gun according to claim 1, comprising locking means mounted coaxially within the cylindrical housing, and means movable to engage said locking means with the body to locate said anvils adjacent said hammer in said first position of the supporting means and movable to release said locking means from the body and eject exploded caps from the anvils in the second position of the supporting means.

3. A toy gun comprising a body, a hammer mounted on, and movable with respect to, said body, a cylindrical housing having a plurality of apertures adjacent its periphery, supporting means secured to said housing and pivotally mounted on said body for selectively moving said housing between a first position in said gun body and a second position projecting from said gun body, a sleeve extending coaxially of said housing inwardly of the said apertures in the housing, a member mounted for movement along said sleeve and having a like plurality of anvils on one end of said member for supporting explosive caps, said anvils being disposed within said apertures, combination locking and ejecting means coaxially mounted for movement within said supporting means for locking together said supporting means and the body to locate the anvils adjacent the hammer in said first position, and for ejecting exploded caps from the anvils in said second position, anvil advancing means mounted on said body and co-operable with said hammer and said member for successively aligning the anvils with said hammer in response to successive movements of the hammer to explode the caps, means projecting inwardly of the outer wall of said housing between adjacent apertures, and means located inwardly of each of said apertures and partially encircling said anvils, said latter two means cooperating to substantially complete a housing around each anvil and to form a labyrinth seal whereby adjacent caps are shielded from an exploding cap.

4. A toy gun according to claim 3, comprising a plurality of teeth formed on said one end of the member, said advancing means comprising a pawl for engaging with one of the teeth in response to each movement of the hammer to rotate the anvils.

5. A toy gun comprising a body, a hammer pivotally mounted on the body, a cylindrical housing having a plurality of apertures adjacent its periphery, bearing means mounted on said body for supporting said housing for rotational movement, said bearing means being selectively movable, together with said housing, between a first position in said gun body and a second position projecting from said gun body, a sleeve extending inwardly of the periphery of said cylindrical housing and coaxial therewith, a member mounted on said sleeve, said member having a plurality of axially extending anvils for supporting

explosive caps, each of said anvils being disposed within one of said apertures, locking means coaxial with, and mounted for movement in, the cylindrical housing, means movable to engage the locking means with the body to locate said anvils adjacent said hammer in said first position of the housing, means mounted for cooperation between said hammer and said member for successively aligning the anvils with said hammer in response to successive operations of the hammer, means projecting inwardly of the outer wall of said housing between adjacent apertures, and means located inwardly of each of said apertures and partially encircling said anvils, said latter two means cooperating to substantially complete a housing around each anvil and to form a labyrinth seal whereby adjacent caps are shielded from an exploding cap, and means movable to release the locking means from the body and eject exploded caps from said anvils in the second position of the bearing means.

6. A toy gun according to claim 5, wherein said means for successively aligning the anvils comprises a pawl movable by said hammer, said member comprising a plurality of teeth engageable by said pawl.

7. A toy gun according to claim 5, wherein said cylindrical housing comprises a plurality of brackets extending into each of said apertures and aligned with said anvils for resisting axial movement of said member when a cap is exploded.

8. A toy gun for exploding cup type explosive caps comprising a body, a hammer pivotally mounted on the body, a cylindrical housing with a front end and with a rear end having a rear cavity therein and a plurality of apertures adjacent its periphery between said cavity and said front end, first radially projecting extensions towards the interior in said cavity between adjacent apertures to form cap housing radially communicating with said cavity, supporting means mounted on said body to support said housing for rotational movement, said supporting means being selectively movable together with said housing between a first closed position and a second open position of the gun, a sleeve extending into the interior of the periphery of said cylindrical housing and coaxial therewith, a member mounted on said sleeve, said member having a plurality of second outwardly radially extending projections, each said second projection being provided with an anvil axially and rearwardly extending to support an explosive cap therein, said member being accommodated in said rear cavity of said cylindrical housing, each of said second projections being included between sets of adjacent first projections to substantially complete said cap housings so as to form a labyrinth between each cap housing and the adjacent cap housings to shield adjacent caps from any exploding cap, each of said anvils being arranged in alignment with one of said apertures within the respective cap housing, locking means coaxial with the cylindrical housing and mounted for movement therein, movable means to engage said locking means with the body to locate said anvils adjacent said hammer in said first position of the supporting means, means mounted for cooperation between said hammer and said member for successively aligning the anvils with said hammer in response to successive operations of the hammer,

and means movable to release the locking means from the body and to axially slide said member and eject exploded caps from said cap housings in the second open position.

9. A toy gun as recited in claim 8, wherein two first adjacent projections from a first portion of a cylindrical wall defining the cap housing and wherein each of said second projections is provided with a second portion of a cylindrical wall spaced from the respective anvil, said cylindrical wall portion completing the cap housing around the anvil with the first portion of the cylindrical wall formed by the pair of first projections, between which said second projection is included.

10. A toy gun as in claim 8, wherein said cylindrical housing includes a plurality of brackets extending in each

of said apertures and aligned with said second projections of said member and with said anvils to resist axial movement of said member when a cap is exploded.
